UNITED STATES PATENT OFFICE.

JOSEPH C. KOOP, OF NEWARK, NEW JERSEY.

SUPPORT FOR FOLDING DOORS.

Application filed November 2, 1923. Serial No. 672,932.

This invention relates to an improved guide for folding doors which is capable of easy adjustment and which is designed to provide a bearing for a roller which 5 travels in a grooved rail and which is held in depressions or inequalities of the rail by reason of a spring which presses down on the ball and its holder and holds the ball in contact at all times with the rail but which 10 under normal travel or pressure is relieved of any support of the door by reason of a limited upward movement of the ball support.

The invention is illustrated in the accompanying drawings in which Figure 1 is a face view partly broken away of the partition with the doors in extended position to close the opening. Figure 2 is a section taken on line 2-2 in Figure 1 and Figures 20 3, 4, 5, and 6 are sections taken on line 3-3 in Figure 1 with the doors in various positions. Figure 7 is an enlarged sectional view of the frame and the door. Figure 8 is a similar view taken at right angles to Figure 7. Figure 9 is a section taken on line 9-9 in Figure 7 and Figure 10 is a perspective view of a pintle situated on the door. Figure 11 is a detail section of a roller on the end of the pintle and Figures 25 12 and 13 are detail perspective and top view respectively, of a modified form of latch.

In the drawing, the door frame is shown equipped with three sets of doors and on one 35 end of the frame is seated a strip 10 to which I prefer to secure one of the doors which consists of the members 12 and 13 which are hinged together as at 14 so that they can fold, the member 12 being hinged 40 as at 15 to the strip 10 since this set of doors need not be slid longitudinally in the frame. The other doors, however, need to be slid to one side and then folded and I show two 45 of such sliding doors, each consisting of a member 16 and a member 17 hinged together at 18.

At the top, the door frame is provided with a slot or groove 19 and each of the door's members 16 has at the top and on the side 50 toward which the doors are slid toward the closed position, a pintle 20, the pintle thus holding the door upright and usually fitting somewhat loosely in the slot so that a roller 21 on the top of the pintle, can roll easily 55 being usually provided with ball bearings 22 as will be evident in Figure 11. Steadying

posts 23 are arranged at the free ends of the doors and have rollers 24 similar to the rollers 21 of the pintle.

The doors are shown extended so as to 60 close the opening in the frame in Figures 1, 2, and 3 and when the opening is to be opened for substantially its full width, the doors 12 and 13 are folded as shown in Figure 4 and then the next door which consists 65 of the members 16 and 17 slid along the door frame until it is adjacent to the folded door and at this point, I dispose a latch which is shown in detail in Figure 9. The latch is placed on the bottom face of the 70 upper rail or the upper member 25 of the door frame and comprises a plate 26 fastened by screws 27 or otherwise, and a swinging latch 28 which is pivoted at 29 to the plate 26 and is held by a spring 30 so that it 75 normally rests substantially parallel with the direction of sliding movement of the door in which position it is maintained by a suitable stop such as the pin 31 shown in Figure 9.

On the pintle 20, I place a lug 32 which projects from the pintle so that when the door is swung, it swings the latch 28 so that it takes a position across the slot as will be 80 evident from Figures 5 and 6 where I show 85 at a the latch in its locking position which prevents any sliding of the door while folded as the lug extends beyond the pivot 29 of the latch. The third door can then be similarly folded as shown in Figure 6.

A modified form of latch is shown in Figures 12 and 13 in which the fixed plate 33 is substituted for the plate 26 and the projecting plate 34 is substituted for the lug 32 and when swung to the dotted position 95 shown in Figure 13, resists any sliding movement of the door while the door is folded.

At the bottom of the doorway, I place a rail 35 which rail is trough-like and at the bottom of the door at each end thereof, as 100 will be seen from Figure 1, I provide a socket 36 which as illustrated, consists of side plates 37, top plate 38 and a bushing 39. The sleeve 40 is screwed into the bushing and is held in adjusted position by a locking 105 screw 41 accessible from the edge or face at the end of the door.

Slidably arranged in the sleeve 40, is a stem 41 with a shoulder 42 which shoulder abuts on the sleeve 40 to support it and has 110 a recess 43 to receive a ball 44 which ball travels in the rail 35. A spring 45 abuts

on the top plate 38 and on the top of the stem 41 and when any inequalities in the rail are present, in view of settling or other reasons, the rail becomes depressed at points, 5 the spring 45 acts to push down on the stem so that the collar and the ball and the rail are always kept in contact.

The ball is placed so that it is substantially central with the axis of the pintle 20 10 at the hinged end of the door and in line with the axis of the supporting post at the other end of the door so that the two members comprising the door are maintained substantially vertical and as a consequence, 15 can slide freely and can be easily pushed from open to closed position and can be folded and unfolded easily.

I claim:

1. A guide for folding doors, said doors comprising a socket including a top plate 20 and a bushing, a sleeve passing through in screw threaded engagement with the bushing, a stem slidable in the sleeve and having

a shoulder to abut on the lower end of the sleeve, a spring abutting on the top plate 25 and extending into the sleeve and held thereby in engagement with the top of the stem, a rail with a groove therein, and a ball in the groove and seated in the shoulder of the stem.

2. A guide for folding doors, said guide comprising a socket including a top plate and a bushing spaced apart, a sleeve open from end to end and screw threaded into the bushing, a stem extending part way up into the sleeve from the bottom and having a shoulder to engage the bottom of the sleeve, the shoulder having a roller on the bottom thereof, and a spring seated in the upper part of the hollow sleeve and abutting on the top plate and end of the stem.

In testimony that I claim the foregoing, I have hereto set my hand, this 1st day of November, 1923.

J. C. KOOP.
